UNITED STATES PATENT OFFICE.

ELLIS W. COOPER, OF BLOOMFIELD, NEW JERSEY, ASSIGNOR TO R. HOE AND CO., OF NEW YORK, N. Y., A CORPORATION OF NEW YORK.

GRIPPER MECHANISM.

1,132,241.

Specification of Letters Patent. Patented Mar. 16, 1915.

Application filed July 1, 1912. Serial No. 706,936.

To all whom it may concern:

Be it known that I, ELLIS W. COOPER, a citizen of the United States, residing at Bloomfield, county of Essex, and State of New Jersey, have invented certain new and useful Improvements in Gripper Mechanisms, fully described and represented in the following specification and the accompanying drawings, forming a part of the

same.

This invention relates to certain improvements in gripper actuating mechanisms for printing and similar machines.

In printing machines and in other machines where the sheets are handled by rotating carriers provided with grippers, such as cylinders, and in which the sheet is transferred from the grippers of one carrier to the grippers of a coöperating carrier, there is liability that the head of the sheet may be torn in the transfer due to the fact that the grippers on the carriers are at the time of the transfer moving in diverging paths.

It is the object of this invention to produce a gripper actuating mechanism which may be employed in connection with rotating sheet carriers by which the sheet may be transferred from the grippers of one carrier to the grippers of the other carrier without

liability of tearing the head of the sheet.

With this and other objects not specifically referred to in view, the invention consists in certain constructions, and in certain parts, improvements and combinations as will be hereinafter fully described and then specifically pointed out.

Referring to the accompanying drawings: Figure 1 represents a plan view of the collecting cylinders of a printing machine embodying the invention. Fig. 2 is a sectional diagrammatic view of the construction shown in Fig. 1 illustrating the action of the gripper mechanism. Fig. 3 is a view similar to Fig. 2 but showing the parts in a different position and also showing the gripper operating mechanism more fully. Figs. 4, 5 and 6 are detail views illustrating successive positions of the grippers during the transferring operation.

Referring to the drawings, 1 indicates a rotating sheet carrier, this carrier being one of the usual collecting cylinders of a printing machine, this cylinder being mounted on a shaft 2 supported in the machine frame in the usual manner. The companion cyl-

inder which in collecting receives the sheet from the carrier is indicated at 3, this cylinder being mounted on a shaft 4. The grippers of the receiver 3 are indicated at 5, these grippers being mounted on a shaft 6. This shaft 6 is provided with an operating arm 7 carrying a roll 8 which is operated in the usual manner by a cam 9 on the machine frame. The construction so far described is a usual one, and it may be remarked that so far as the grippers on the cylinder 3 are concerned any suitable form of gripper operating mechanism may be employed.

In mechanisms constructed in accordance with the invention, the grippers on the cylinder 1 or the carrier which first receives the sheet and delivers it to the receiver, will, on one revolution of the carrier, open to receive the sheet in advance of what may be termed the sheet taking line of the receiver, and on the revolution on which the sheet is delivered, will open beyond the sheet taking line. By thus constructing the grippers of the first cylinder they may be caused to substantially follow during the sheet releasing operation the movement of the sheet receiving surface of the cylinder to which the sheet is delivered. Further, in the best constructions embodying the invention, the grippers will be operated by a single actuator, such as a cam, the position of which is shifted between the sheet taking and sheet releasing operations.

In the particular construction selected to illustrate the invention, the grippers 10 of the cylinder 1 are mounted on a shaft 11, this shaft being journaled in the ends of the cylinder as usual, and being provided with an operating arm 12 which carries a roll 13. This roll 13 runs in a groove 14 of a closed or box cam 15 loosely mounted on the shaft 2. The box cam carries a stud 16 to which is connected an adjustable connecting rod 17 in turn connected at 18 to a cam lever 19 on a shaft 20. This lever 19 carries a roll 21 which runs in a groove 22 of a cam 23 mounted on an operating shaft 24 which extends across the machine. In the particular construction illustrated, this shaft 24 makes one revolution to each two revolutions of the shaft 2. The effect of the cam 23 and the connections before described is to shift the position of the box cam 15 on every revolution of the cylinder 1. The position of the box cam at the time the grippers 10 of

the carrier have been opened to receive the head of the sheet is shown in Fig. 2. As the cylinder rotates from the position shown in Fig. 2 the grippers 10 are caused to close down upon the sheet and it is carried onward by the cylinder 1 until the parts reach the position shown in Fig. 3. When the parts reach the position illustrated in Fig. 3, the sheet held by the grippers 10 is about 5 to be transferred to the grippers 5 of the cylinder 3, a second sheet being at this time in position to be also taken by the grippers 5 and collected with the sheet on the cylinder 1. At this time the cam 23 and connections 10 before described have shifted the box cam from the position illustrated in Fig. 2 to the position illustrated in Fig. 3.

In the particular construction illustrated what may be termed the opening part of the 20 cam is marked *a* and what may be termed the closing part is marked *b*. The opening part of the cam is given such shape that, as the grippers pass from the position shown in Fig. 3 to the position shown in Fig. 5, 25 they substantially follow the path of movement of the sheet receiving surface of the cylinder 3. The opening movement is further such as to cause the grippers 10 to move slightly faster than the movement of the 30 sheet receiving surface of the cylinder 3, so that they not only release the sheet on the cylinder 1 but at the same time are withdrawn from between that sheet and the sheet with which it is to be collected. By causing 35 the grippers 10 to open in advance of what has been termed the sheet releasing line as they take the sheet, plenty of time is given them for their operation. Further, by causing the grippers to open to release the sheet 40 just beyond the sheet releasing line accurate register of the two sheets to be associated is obtained. Further, as the movement of the grippers 10 in releasing the sheet follows the path of movement of the sheet receiving surface of the other cylinder, the 45 grippers 10 do not need to let go of the sheet until it is taken by the grippers 5 of the other cylinder, so that the sheet is at all times under control, and there is no liability 50 of such register being shifted. Further, by employing a single actuator a very simple and efficient construction and one which operates very easily is produced.

Changes and variations may be made in 55 the construction by which the invention is carried into effect. The invention claimed, therefore, is not to be confined to the particular construction herein described and illustrated in the accompanying drawings.

60 What is claimed is:—

1. In combination, a rotating sheet carrier provided with grippers, a rotating sheet receiver provided with grippers to which the carrier delivers the sheets, and 65 means for opening the grippers of the

carrier at one position in space in advance of the sheet taking line of the receiver on one revolution and at a different position in space beyond said sheet taking line on the succeeding revolution.

70

2. In combination, a rotating sheet carrier provided with grippers, a rotating sheet receiver provided with grippers to which the carrier delivers the sheets, and a single actuator for operating the grippers of the 75 carrier, said actuator operating to open the grippers at one position in space in advance of the sheet taking line of the receiver on one revolution and at a different position in space beyond said sheet taking line on the 80 succeeding revolution.

75

3. In combination, a rotating sheet carrier provided with grippers, a rotating sheet receiver provided with grippers to which the carrier delivers the sheets, and means 85 for oscillating the grippers on the carrier to release the sheet as the grippers of the receiver close thereon, said means so oscillating said grippers as to cause their sheet-holding portions to substantially follow the 90 path of movement of the surface of the receiver during and after the sheet releasing operation.

85

4. In combination, a rotating sheet carrier provided with grippers, a rotating sheet 95 receiver provided with grippers to which the carrier delivers the sheets, a single actuator for opening the grippers of the carrier to release the sheet as the grippers of the receiver close thereon, said actuator causing 100 the sheet holding portions of its grippers to substantially follow the path of movement of the surface of the receiver during and after the sheet releasing operation.

95

5. In combination, a rotating sheet carrier provided with grippers, a rotating sheet receiver provided with grippers to which the carrier delivers the sheets, an actuator for the grippers of the carrier, and means 105 for shifting the position of the actuator to cause the grippers to open at one position in space in advance of the sheet taking line of the receiver on one revolution and at another position in space beyond the sheet taking line on a succeeding revolution.

105

6. In combination, a rotating sheet carrier provided with grippers, a rotating sheet receiver provided with grippers to which the carrier delivers the sheets, an actuator cam 120 for the grippers of the carrier, and means 120 for shifting the position of the cam to cause the grippers to open at one position in space in advance of the sheet taking line of the receiver on one revolution and at another position in space beyond the sheet taking 125 line on a succeeding revolution.

115

7. In combination, a rotating sheet carrier provided with grippers, a rotating sheet receiver provided with grippers to which the carrier delivers the sheets, an actuator cam 130

for the grippers of the carrier, said cam being mounted upon and movable about the shaft of the carrier, and means for shifting the position of the cam to cause the grippers to open at one position in space in advance of the sheet taking line of the receiver on one revolution and at another position in space beyond the sheet taking line on a succeeding revolution.

10 8. In combination, a rotating sheet carrier provided with grippers, a rotating sheet receiver provided with grippers, to which the carrier delivers the sheets, an oscillatory actuator for the grippers of the carrier, and 15 means for oscillating the actuator to cause the grippers to open at one position in space in advance of the sheet-taking line of the receiver on one revolution and at another

position in space beyond the sheet-taking line on a succeeding revolution.

9. In combination, a rotating sheet carrier provided with grippers, a rotating sheet receiver provided with grippers, to which the carrier delivers the sheets, and means for opening the grippers of the carrier at 20 alternately different positions in space on the side adjacent the said receiver during alternate revolutions of the carrier.

In testimony whereof, I have hereunto set my hand, in the presence of two subscribing 25 witnesses.
